UNITED STATES PATENT OFFICE.

JESSE G. MAHAN, OF PANA, ILLINOIS, ASSIGNOR TO ROBERTS AND SCHAEFER COMPANY, OF CHICAGO, ILLINOIS, A CORPORATION OF ILLINOIS.

GUIDE PLATE FOR DRY SEPARATORS.

Application filed February 6, 1924. Serial No. 690,892.

My invention relates to improvements in dry concentrators. It has for one object to provide a new and improved form of deflector blades for dry separators and means for fastening and adjusting the same. The deflector to which I refer is adapted to be used in connection with a dry separating table or any other similar apparatus wherein material which has been separated or treated is fed over the edge of a guide plate or surface and falls more or less freely by gravity. The deflecting blade with which I am concerned is a blade which may be set by the operator to deflect and separate the refuse from the middlings and the middlings from the coal when used in connection with a coal table or from the ore or metal when used in connection with a metal separating table. The idea is that as the separation takes place, the line of demarkation between refuse, middlings and material to be saved varies slightly and in order to properly segregate the material it is incumbent upon the operator to watch the flow of material across the table and to adjust the deflecting blade from time to time so as to make the cut between the various materials. It is essential, therefore, that the deflecting blade be rigid, durable, and remain in place and still be quickly, easily and accurately adjusted by the operator. Other objects will appear from time to time in the specification.

My invention is illustrated more or less diagrammatically in the accompanying drawings, wherein—

Figure 1 is a plan view;

Figure 2 is a front elevation;

Figure 3 is a section along the line 3—3 of Figure 1;

Figure 4 is a detail plan view of the deflector;

Figure 5 is a section along the line 5—5 of Figure 4;

Like parts are indicated by like characters throughout the drawings and specification.

A is a separating table. I have shown it as an air separating table wherein air is fed under pressure into the box A¹ beneath the table. It works up through the table and through the flowing stream A² of material fed to the table through the feed spout A⁴. A⁵ is a reciprocating mechanism whereby the table is vibrated and A⁶ is a chute or guide plate adapted to receive the discharge of

material from the table. A⁷, A⁸ and A⁹ are chutes receiving material from the guide plate and adapted to discharge the refuse, the middlings and the coal respectively into bins or to any suitable storage or handling place.

B is a supporting hanger or beam extending across the face of the guide plate A⁶. This beam is slotted as at B¹. Interposed between this beam and the face of the chute are a series of baffles or deflector blades C. These blades may take the form of channels or I-beams as indicated or any other suitable form. They are of such width as to fit snugly between the beam and the inner face of the chute and are shod with felt or other suitable flexible packing material B³ where they engage the plate so as to make a substantially dust tight closure between the deflector and the plate without making it necessary to exert too great a pressure therebetween.

The upper flange of the deflector C is slotted as at C¹. A bolt having a large head C² penetrates through this slot, the bolt head engaging the deflector blade to prevent turning. This bolt also passes through the slot in the beam and is engaged by a threaded shank C³ having a hand wheel C⁴ adapted to be manipulated by the operator. When the operator releases the hand wheel, the pressure of the end of the threaded shank on the beam and the constriction of the bolt is released and the operator can then move the deflector plate longitudinally or laterally or can rotate it to bring it in any desired adjusted position.

The hand wheel is comparatively large so that when he releases the tension, the operator has something to hold on whereby he can manipulate the deflector plate and the hand wheel can be clamped, thereby locking the parts into proper working position without delay.

The packing strip preferably takes the form of a compressible piece of felt or the like but the yielding compressible effect might be obtained by other means as for instance, by the use of a downwardly projecting flexible strip.

It will be evident that while I have shown in my drawings an operative device, still many changes might be made in the size, shape and disposition of parts without de-

parting materially from the spirit of my invention and I wish, therefore, that my showing be taken as in a sense diagrammatic.

I claim:—

3. The combination with a concentrating table of a guide plate arranged immediately below the discharge edge thereof a fixed support placed in front of the deflecting plate, there being sufficient clearance between the support and the plate to permit the discharge of the concentrated material between them, a deflecting blade interposed between the support and the plate, means associated with the support for positively holding the deflecting blade in adjusted position, said means being adapted when released to loosely hold the deflecting plate and prevent its displacement by the material and permit its manual adjustment. 45 50 55

4. The combination with a concentrating table of a guide plate arranged immediately below the discharge edge thereof, a fixed support placed in front of the deflecting plate, there being sufficient clearance between the support and the plate to permit the discharge of the concentrated material between them, a deflecting blade interposed between the support and the plate, means associated with the support for positively holding the deflecting blade in adjusted position, said means being adapted when released to loosely hold the deflecting plate and prevent its displacement by the material and permit its manual adjustment, the support being slotted, the holding means comprising a bolt and hand wheel, the bolt passing through the slot in the supporting means, the deflector blade being flanged, there being a slot in the flange to engage the bolt. 60 65 70 75

Signed at Chicago county of Cook and
State of Illinois, this fourth day of Febru-
ary 1924.
